UNITED STATES PATENT OFFICE.

JOHN C. HUNTER, OF NEW BRITAIN, CONNECTICUT.

FOUNTAIN SPRAY-BRUSH.

1,118,774.

Specification of Letters Patent. Patented Nov. 24, 1914.

Application filed February 27, 1914. Serial No. 821,443.

To all whom it may concern:

Be it known that I, JOHN C. HUNTER, a citizen of the United States, residing at New Britain, in the county of Hartford and State of Connecticut, have invented certain new and useful Improvements in Fountain Spray-Brushes, of which the following is a specification.

My invention relates to improvements in fountain spray brushes of the type used in the bath and the object of my improvement is simplicity and economy in construction and convenience and efficiency in use.

In the accompanying drawing:—Figure 1 is a front elevation in part broken out and in section of my improved fountain spray brush. Fig. 2 is a side elevation of the same, the brush proper being in part broken away, and the outline of the brush being shown in dotted lines. Fig. 3 is a rear elevation of part of the same. Fig. 4 is a fragmentary sectional view on an enlarged scale on the line $\alpha\alpha$ of Fig. 3.

My fountain spray brush comprises a brush proper 10 and a spraying device 11 constructed and combined in a special manner.

The brush proper 10 is of inverted U shape as viewed in front elevation and has a pronounced bend at about the middle as shown at 12, as shown in side elevation, suitably to fit curved portions of the body.

The spraying device 11 comprises a perforated portion 16 which is positioned axially between the arms of the U of the brush and has a bend as shown at 13 to correspond to the bend 12 of the brush proper 10. The portion of the spraying device 11 outwardly from the bend 13 is relatively short, the end 14 thereof being appreciably separated from the opposed apex portion 15 of the brush proper 10. The said spray portion 16 is made of round tubing appreciably flattened and is provided with a plurality of perforations 17 in the side and front wall and the free end 14 already mentioned is flattened still more than the body portion and so that the round hole corresponding to the bore of the original tubing assumes the form of a wide slit 18 at the extreme end.

The brush proper 10 and the spraying device 11 are mounted on a suitable handle 19.

The preferred form of construction of my fountain spray device is as follows:—The handle 19 is elongated; has an axial bore 20, to fit the cylindrical tubular lower extension

21 of the spraying device 11; has a relatively wide head 22 at the upper end; has a pair of grooves 23 extending one on each side of the head 22 from the extreme upper end inwardly for an appreciable distance, and inwardly directed holes 24 at the inner end of each of the said grooves 23; has the extreme upper end faced off adjacent the bore 20 suitably to serve as a seat for a securing plate 25 at the junction of the spray portion 16 and the downward extension 21 of the spraying device 11 and which is secured by pins 26; and is provided adjacent the said extreme upper end with a holding strip 27 passing around the sides and across the grooves 23 and which is placed in position after the lower ends 28 of the brush proper 10 have been placed in the said grooves 23, being secured by suitable pins 29.

The brush proper 10 comprises a frame 30 composed of a pair of wires twisted together with the bristles 31 positioned between the same in an ordinary manner. The frame 30 is bent into U shape; is provided with the bend 12 already mentioned; the lower ends 28 thereof fit into the grooves 23, and they are provided at the extreme lower ends with inwardly bent portions 32 that fit in and are positioned in the holes 24. The holding strip 27 extends across one face, as the rear face, of the head 22; passes around the lateral edges of the head 22; and has the front ends secured to the front face of the head 22 by the pins 29. A pin 29 may also be provided in the portion extending across the rear face of the head 22.

The spraying device 11 comprises the perforated portion 16 flattened as described at the upper end; the cylindrical extension 21 at the lower end, extending through the handle 19, and having the extreme lower end projecting beyond the handle 19 suitably to receive the end of a rubber tubing; and the securing plate 25 at the junction of the said flattened perforated portion 16 and the cylindrical portion 21 and which is secured to the said junction in some suitable manner, as by soldering. The securing plate by means of the pins 26 serves to secure the spraying device in the handle 19, and the holding strip, by means of the pins 29 serves to hold the brush proper 10 to the handle 19.

The holes 24 are in alignment and extend through the wall of the handle 19 to the

bore 20 and are in fact made by one drilling through the handle.

The wire frame of the brush serves as a guard for the spray portion, which is flattened as described, and therefore the spray portion can be made appreciably shorter than the brush frame as shown and without danger when in use.

To provide extra spraying effect to off-
set the feature of reducing the relative over-
all length of the spraying device I provide
the axial opening 18 in the end of the
spraying device. The said opening being
in the form of a slit, serves to deliver water
suitably to be distributed effectively by the
bristles 31 at the end of the brush. The
slit 18 is formed by flattening the end of
the tube of which the spray device is
formed, thus elongating the original circu-
lar bore of the said tube. The flattening
of the end of the tube described besides ef-
fecting the elongating of the delivery por-
tion also serves to taper the said end so that
the extreme end or tip portion is appreci-
ably reduced relatively to the wire frame
of the brush, suitably to be effectively
guarded thereby when in use. That is to
say, the reduction of the end of the tube
serves to bring the dimensions of the same
down within limits suitably to be guarded
by the wire frame when in use, and by ef-

fecting such reduction in such a manner as
to provide an axial opening at the end, a
delivery opening is provided at the end
suitable for coöperating with the bristles 35
at the end of the brush so as to produce an
effective distribution of the water at the
said end of the brush.

I claim as my invention:—

In a fountain spray brush, a brush proper 40
comprising a frame of wire of U-shape and
bristles distributed along the said frame,
the ends of the said frame being secured in
a handle, a spraying device extending from
the said handle, the said spraying device 45
comprising a tubular structure, positioned
axially between the arms of the said U-
shaped frame, and having perforations in
the side wall suitable for delivering water to
the bristles adjacent thereto, and the said 50
spraying device being appreciably shorter
than the said frame by which it is inclosed
and being provided with an axial opening
at the extreme end suitable for delivering
water to the bristles relatively remote from 55
the said spraying device at the end portion
of the brush.

JOHN C. HUNTER.
